United States Patent Office.

RUSSELL B. ANDREWS, OF POLAND, MAINE.

Letters Patent No. 96,655, dated November 9, 1869.

IMPROVED COMPOSITION-PANEL FOR DOORS.

The Schedule referred to in these Letters Patent and making part of the same.

To all whom it may concern:

Be it known that I, Rev. RUSSELL B. ANDREWS, of Poland, in the county of Androscoggin, and State of Maine, have made a new and original Improvement in Panel-Doors, also panelling of all kinds; and I do hereby declare that the following is a full and exact description thereof, reference being had to the accompanying drawings, and to the letters of reference marked thereon.

The nature of my invention consists in using suitable paper, (or junk-board,) colored or uncolored, grained or ungrained, for panels, instead of wood, the frame to be made of wood, in the usual manner; and I do hereby declare that the following is a full, clear, and exact description thereof, which will enable others skilled in the art to make and use the same, reference being had to the accompanying drawing, furnishing part of this specification.

I construct the frame-work of doors in any of the known forms, also the frame-work to all kinds of pan-

elling, either by mortise and tenons with grooves, or with dowels and grooves, then insert paper, (or junk-board,) for panels, instead of wood.

The figure, in the accompanying drawing, represents my new improved door.

A is the top rail,

B is the middle rail,

C is the bottom rail,

D and E are the long and short mountings, and

E and F are the two stiles, which constitute the frame-work.

F F F and F are the four paper panels.

What I claim as new, and desire to secure by Letters Patent, is—

An improved panel for doors, made of paper or junk-board, substantially as herein described.

REV. R. B. ANDREWS.
